UNITED STATES PATENT OFFICE.

JOSEPH C. MARTIN, OF FLORENCE, MASSACHUSETTS.

CASH-CARRIER.

SPECIFICATION forming part of Letters Patent No. 334,599, dated January 19, 1886.

Application filed November 30, 1885. Serial No. 184,295. (No model.)

To all whom it may concern:

Be it known that I, JOSEPH C. MARTIN, of Florence, county of Hampshire, State of Massachusetts, have invented an Improvement in 5 Cash-Carriers, of which the following description, in connection with the accompanying drawings, is a specification, like letters on the drawings representing like parts.

My invention, relating to a cash carrier or 10 conveying device such as employed in stores, is shown embodied in an apparatus of that kind in which the carrier moves along a track between the different points or stations in the store, being propelled by gravity, or by some 15 external propelling force, the carrier being shown in this particular instance as propelled by a pneumatic projecting device along a track which is crowning or arch-shaped, being higher at an intermediate point than at either 20 end, so that when the carrier has been propelled from either end by a force sufficient to carry it beyond the middle or highest point of the track the carrier will continue its movement to the other end of the track by gravity. Carriers 25 of this kind usually run at such a height above the floor as not to be in danger of striking persons or other objects, and the receptacle for the cash or article to be conveyed usually has an up-and-down movement from the level 30 of the carrier, to facilitate the application to and removal from the carrier of the cash or article to be conveyed.

One object of the present invention is to produce a simple, convenient, and durable 35 carrier; and the main feature of this part of the invention consists in connecting the receptacle for the article to be conveyed with the main portion of the carrier that runs on the track by a hinged or pivoted spring- 40 pressed arm, by which the receptacle may be raised to or lowered from the level of the carrier. The receptacle is shown as a flat tray of proper size and shape to receive a book—such as commonly employed for making memoranda 45 of the sales—and the main body of the carrier is provided with a holder which rests upon the book when in position in the tray, keeping it tightly closed, so that the money will be retained securely between the leaves of the 50 book.

The invention also consists in the novel construction of the track and running-gear of the

carrier co-operating therewith, and also in the pneumatic propelling device, and in various details of construction hereinafter pointed out.

Figure 1 is a side elevation of a cash-carrier or conveying apparatus embodying this invention, the receptacle being shown in dotted lines as drawn down to the position convenient for applying or removing its contents, and being shown in full lines in the position occupied while moving from point to point, and the projector being shown in the position assumed just before its impulse is imparted to the carrier; Fig. 2, an end elevation of the carrier, showing the track in cross-section; Fig. 3, a horizontal section on line *x* *x*, Fig. 2, looking downward; Fig. 4, a detail showing the joint or hinge of the receptacle-arm in plan view on a larger scale than in the other figures; Fig. 5, an enlarged longitudinal section of the receptacle and holder with a book held therein, and Fig. 6 a longitudinal section of the projecting device on a larger scale than in Fig. 1.

The track *a* is shown as consisting of a flat strip of metal beveled at its edges to form V-shaped rails or guides *a'*, which co-operate with the running-gear of the carrier. The track *a* is sustained by suitable supports, *a''*, and is preferably inclined upward from either end, as shown in Fig. 1, toward an intermediate point, so that if the carrier receives an impulse sufficient to carry it by the intermediate highest point it will continue on to the other terminal or station by gravity, making the passage in less time than if propelled by a force just sufficient to carry it across in a substantially horizontal line. This feature of inclining the track upward from either end is not herein claimed, as it has been previously shown and described by me. The running-gear of the carrier consists, essentially, of two pairs of wheels, *b*, having their peripheries provided with V-shaped grooves fitting the V-shaped edges of the track *a*, the said wheels running upon journals *b'*, which support the main frame-work *c* of the carrier. The track *a* is preferably curved in cross-section, as shown in Fig. 2, so that the wheels *b* are inclined, although they might be in any position from the horizontal to the vertical.

To the lower end of the frame *c* is fastened

a rigid arm, *e*, (shown as composed of a piece of stout wire or rod,) the two extremities of which are fastened in the frame-work *c*, and the middle portion of which is bent transversely, as shown at *e'*, Fig. 4, forming one member of the hinge or joint for the movable arm *f*, that supports the receptacle, *g*, for the cash or other article or material to be conveyed. The said receptacle *g* is shown in this instance as a flat tray open at its forward end, but provided with ledges *g'* along its sides and rear end, the said receptacle being of proper size to receive the memorandum-book *h*, (see Fig. 5,) between the leaves of which the cash or money may be placed. The receptacle *g* is preferably pivoted or swiveled in the arm *f*, which is forked to embrace it, as best shown in Figs. 2 and 3, so that the said receptacle may retain its substantially horizontal position during its oscillating movement upon the arm *f* toward and from the main frame-work *c* of the carrier. The arm *f* may be composed of a stout wire or rod secured at its end upon a hinge-piece, *f'*, (see Fig. 4,) having lugs *f''*, which turn upon a transverse portion, *e'*, of the fixed arm *e*, and being acted upon by a spring, *i*, which tends to turn the arm *f* toward the arm *e*, or from the dotted to the full line position, Fig. 1, thus pressing the receptacle *g* upward. The frame *c* is provided with a holder, *k*, shown as consisting of a wire frame of proper shape to bear along the edges and across the end of the book *h*, as shown in Fig. 5, when the tray containing the said book is pressed upward by the spring *i* toward the said holder, thus securely confining coins or other material which may be placed between the leaves of the book *h*, as shown at *m*, Fig. 5. The receptacle *g* is provided with a handle, *n*, extending downward beneath it in line with the pivotal joint between the receptacle and arm *f*, so that in pulling down upon the said handle the receptacle *g* is retained horizontal, or in proper position to readily receive the book *h*, or permit it to be removed therefrom. The handle *n* may also be used to receive the propelling force when the carrier is to be propelled or thrown along the track by the operator.

Instead of throwing the carrier by hand, the apparatus may include a pneumatic projecting device consisting of a cylinder, *p*, closed at one end, and containing a piston, *p'*, connected with the rod *p''*, working in a guide-passage in the head *p''* of the cylinder, which is preferably open, as shown in Fig. 6, so that when the piston *p'* is moved quickly toward the closed end of the cylinder the air will be compressed behind it, and if the piston is then released the compressed air will throw it forward. The end of the piston-rod outside the cylinder is provided with a cushion, *p'*, which may be of soft rubber or other yielding and preferably elastic material, and which is properly located to engage the frame-work *c* of the carrier, so that when the piston is thus thrown forward it will project or throw the carrier along the track

with sufficient power to carry it over the high part of the track, so that it will be carried to the station at the other end of the track. The piston is moved toward the closed end of the cylinder and then released, so as to first compress and then be impelled by the air between it and the closed end of the cylinder, by means of an actuating device consisting of a rod or slide-bar, *r*, having an endwise movement in guides *r'*, which may be made in the brackets by which the cylinder is fastened to the track *a* or other frame-work at the proper position near the end of the track. The said slide-bar is acted upon by a spring, *r''*, (see Fig. 1,) tending to move it forward to the position shown in Fig. 6, and the said rod is provided with a catch or engaging device, *r'*, which, when in its forward position, engages the flange *p'* at the end of the piston-rod. The slide-bar *r* is connected with an actuating-cord (see Fig. 1) passing over a pulley, *t*, and provided with a handle, *t'*, accessible to the operator, who, by pulling down upon the said handle, moves the slide-bar *r* backward to the position shown in Fig. 1, carrying the piston-rod and piston with it, and compressing the air at the back of the piston. The conveying device follows the cushion *p'* at the end of the piston-rod by gravity as the latter is moved back, remaining in contact therewith, as shown in Fig. 1, and at the end of the backward movement the catch *r'* is disengaged from the flange *p'* by a tripping device, *r''*, engaging an inclined portion, *r''*, of the catch and operating the same, as indicated in dotted lines, Fig. 6, so that the piston is released, and is at once impelled forward by the compressed air behind it. When the operator releases the handle *t'*, the slide-rod *r* is drawn forward by the spring *r''*, so as to engage the piston and its rod for the next operation. The cushion *p'*, together with the air at the rear of the piston, serves as a bunter to arrest the carrier without concussion when it arrives at the station.

It is obvious that a propelling device of this kind will operate with carriers of various construction, and also that the herein-described carrier, with its receptacle and means for moving the same downward from the track, may be employed with any kind of running-gear and track and means for propelling the carrier along the track, either by hand or wholly by gravity, or by any other suitable propelling device.

I claim—

1. In a conveying device, the combination, with the body or main portion, of a pivoted arm and receptacle connected with the free end of the said arm, substantially as described.
2. The combination of the main portion of a carrier with a pivoted arm and receptacle connected with the free end thereof, and a holder connected with the main portion of the carrier and co-operating with the said receptacle, substantially as described.
3. The combination of the main portion of

a carrier with an arm pivoted thereto, and a receptacle pivotally connected with the free end of the said arm, substantially as described.

4. The combination of the main portion of 5 a carrier with an arm pivoted thereto, and a receptacle pivotally connected with the free end of the said arm, and provided with a handle in line with its joint with the said arm, substantially as described.

10 5. The combination of the main portion of a carrier with a spring-pressed arm pivoted thereto, a receptacle consisting of a flat tray adapted to receive a book connected with the said arm, and a holder connected with the 15 main portion of the carrier, having parts which bear along the sides and across the end of a book in the said receptacle, substantially as described.

6. In a conveying apparatus, a pneumatic 20 projecting device comprising a cylinder closed at one end, a piston working therein, combined with an actuating device having an engaging device, by which the piston is moved to compress the air in the cylinder, and a co-operating 25 releasing device, by which the piston is disengaged and permitted to be acted upon by

the air previously compressed by it, substantially as described.

7. In a conveying apparatus, a track provided with lateral guides or rails, combined 30 with a carrier comprising frame-work and supporting-wheels bearing laterally on the track which lies between them, the frame-work hanging from the said wheels below the said track, substantially as described.

35 8. The combination of the track inclined upward from its terminal stations with a projecting device consisting of a cylinder closed at one end, a piston working therein and connected with a cushion that engages the carrier, 40 and an actuating slide-rod provided with a catch, by which it may be connected with said piston to move the same into the cylinder, and a releasing device for disengaging the said catch, substantially as described.

45 In testimony whereof I have signed my name to this specification in the presence of two subscribing witnesses.
